UNITED STATES PATENT OFFICE.

MERITT HUTTON, OF ST. BENEDICT, PENNSYLVANIA, ASSIGNOR TO REMBRANDT PEALE, OF NEW YORK, N. Y.

CAR-HAULING MECHANISM.

Original application filed August 24, 1920, Serial No. 405,699. Divided and this application filed September 24, 1921. Serial No. 502,879.

To all whom it may concern:

Be it known that I, MERITT HUTTON, a citizen of the United States, residing at St. Benedict, in the county of Cambria and State of Pennsylvania, have made certain new and useful Improvements in Car-Hauling Mechanism, of which the following is a specification.

The invention relates to an automatic car hauling device, and more particularly to a novel device or mechanism adapted to automatically engage and propel coal cars and the like.

This application is a division of my co-pending application Ser. No. 405,699, filed August 24, 1920.

The accompanying drawings, referred to herein and constituting a part hereof, illustrate one embodiment of the invention, and together with the description, serve to explain the principles of the invention.

Of the drawings:

Fig. 1 represents a section of a track and of the automatically operating car handling mechanism and a car being propelled thereby;

Fig. 2 is a detail side elevation of the car engaging and propelling device;

Fig. 3 is a horizontal section taken through the device of Fig. 2, on the line 3—3, looking in the direction of the arrows;

Fig. 4 is a vertical transverse section taken on the line 4—4 of Fig. 2, looking in the direction of the arrows;

Fig. 5 is a horizontal section, on a reduced scale, taken on line 5—5 of Fig. 2, and showing the car propelling device passing around a curve; and

Fig. 6 is a transverse vertical section, taken on the line 6—6 of Fig. 1, looking in the direction of the arrows.

The invention provides novel mechanism for handling cars along tracks and in certain of its features more particularly for handling the full and empty cars on a mine dump, receiving a train or "trip" of full cars and running them one at a time to the dump and returning the empty cars to be made up into a train or "trip" on another track to be returned into the mine.

As a part of the foregoing, the invention provides a novel and highly efficient form of car engaging and propelling device, adapted to feed or propel the loaded cars forward-

ed as required for dumping, and for feeding 55 or propelling the empty cars along an inclined track to bring them to grade on a storage, or train making track, to be returned to the mine.

Other features of the invention will be set 60 forth in connection with the following detailed description of the illustrated embodiment.

Referring preliminarily to the general features of the embodiment of the invention, 65 illustrated by way of example in the accompanying drawings, a novel car engaging and propelling device is provided, adapted to run upon and to be held down by a single rail, preferably of I beam form. This car 70 propelling device is connected at each end to a cable, which is adapted to draw the device in either direction, that is, either backwardly or forwardly.

The tracks are arranged preferably with a 75 very slight gradient for a long train of loaded cars whereby a single car propelling device engaging the rear car will gradually progress or propel the entire train slowly forwardly the foremost car being successively detached and run forward over the dump, and after being dumped and being run on to an automatic switch which runs it, or them, successively back on the empty tracks.

The travel of the car haul or propelling device on the empty track is preferably relatively short, and it may be arranged to elevate the cars one at a time up a short incline, and to return idle and rapidly after each car 80 is so elevated to take up the next succeeding car, the tracks being inclined sufficiently to permit the empty cars to run there along and be strung together ready to be coupled into a train to return into the mine. 85

Referring now in detail to the embodiment of the invention illustrated by way of example in the accompanying drawings, this device is adapted to run along a single rail, and the device and rail are so constructed 100 and arranged that the rail not only supports and guides the hauling device, but the hauling device is held down in position at all times by the rail, while being free to run therealong.

In this present illustrative embodiment, a rail 1 is provided, which may be of ordinary I beam cross-section, and this rail may

be laid down between the track rails, and may be spiked or otherwise fastened to the floor or ties 2 or other support for the track rails.

5 The car hauling device comprises two plates 3 and 4, vertically disposed alongside, and extending upwardly above, the supporting and guiding rail 1. In the greater part of their length the plates 3 and 4 are spaced

10 apart to hold or include between them the wheels or rollers upon which the device runs and also to hold the car engaging device or dog. At each end the plates 3 and 4 are preferably bent inwardly with a double bend

15 so that they are in contact with each other, as shown at 5 and 6 in Fig. 3. The hauling

chains or cables, or equivalent device 7 may

be fastened into apertures 8 in the ends 5

and 6 of the hauling device.

20 As embodied, the hauling device is supported and progressed along the rail 1 by two rollers or wheels 9 and 10 located, respectively, near either end of the device. These rollers are rotatably mounted on spac-

25 ing sleeves or bushings 11 and 12, respectively, against the ends of which sleeves the plates 3 and 4 abut, and are thus properly spaced apart. The sleeves 11 and 12 are centrally internally longitudinally apertured,

30 and bolts 13 and 14, respectively, pass through these apertures and through aligned apertures in plates 3 and 4. On bolts 13 and 14 respectively are screw-threaded nuts 15 and 16, the bolts thus serving to hold the

35 plates 3 and 4 together against the ends of the spacing sleeves 11 and 12, while the

rollers 10 and 9, journaled on the sleeves, are

free to rotate as the hauling device moves

along the rail 1.

40 In the embodied form of means for holding the hauling device down to the rail, there are provided near each end of the device, rollers 17 and 18, located on the inner side of the plates 3 and 4, and projecting in-

45 wardly beneath the top flange or tread 19 of the rail 1. The rollers 17 and 18, respec-

tively, are mounted upon stub shafts 20 and 21, shouldered so to hold the rollers jour-

naled thereon, and they are also shouldered

50 to pass through apertures in the plates 3 and 4, so that the rollers are held in position while being free to rotate. The shafts 20

and 21 are screw-threaded on their exterior ends to receive nuts 22 and 23 to secure them

55 in position. There are preferably a pair of these rollers at either end of the device.

The hauling device is thus free to travel

60 along the rail 1 upon the rollers 9 and 10, while the rollers 17 and 18 prevent the de-

vice lifting from the rail while not interfer-

ing with its travel along the rail.

Referring now to the embodied form of car engaging device or dog, that is, the de-

vice supported upon the foregoing structure

65 which engages with the car to propel it

along the tracks movable and preferably pivoted dog 28 is provided, having an upwardly projecting part 29 adapted to engage with some part of the car 40, such as a plate 41 extending downwardly from beneath the car bottom. The dog has a tail 30, which acts as a restoring weight for the rocking dog, as later described. The car 40 as shown has the usual two pairs of wheels 42, running on tracks 43 and 44.

70 The dog 28 is pivotally mounted on a spacing sleeve 31 extending crosswise between, and having its end abutting on, the inner sides of the plates 3 and 4. The sleeve 31 is internally centrally and longitudinally apertured and therethrough passes a bolt 32, which passes likewise through corresponding apertures in the plates 3 and 4. The bolt 32 takes a nut 33, the bolt thus serving to hold the plates 3 and 4 against the ends of the spacing sleeve 31, thus holding the plates together properly spaced apart, and leaving the dog 28 free to pivot on the sleeve 31.

75 As constructed, the dog 28 will rock from right to left in Fig. 2 to permit a car to pass going in the left hand direction, as shown in the dotted line position of Fig. 2. The dog 28, however, in the full line position of Fig. 2 is rigid against any movement to the right hand about its pivot, so that it will push any car engaged by the dog on the left hand side thereof in the left hand direction in Fig. 2. To facilitate a car passing the dog while traveling from right to left in Fig. 2 the end 29 of the dog is provided with a rear beveled face 34, against which the car may strike and thereby rock the dog to the dotted line position to permit the car to pass, as already explained.

80 A suitable stop to limit the rocking movement of the dog in this direction is provided by a bolt 35 passing through apertures in the plates 3 and 4 and provided with a nut 36. A similar stop with which the tail of the dog is adapted to engage is provided at the other side by a bolt 37 passing through the plates 3 and 4, and provided with a nut 38. The tail 30 is weighted or is sufficiently heavy to restore the dog to the full line position of Fig. 2 after the car has passed.

85 In Fig. 5 the device is shown passing around a curve. Side pulleys 45 and 46 are shown for the cable 7.

90 It will be understood that departures may be made from the details of invention as herein embodied and described within the scope of the appended claims without departing from the principles of the invention and without sacrificing its chief advantages.

95 What I claim is:—

1. A car hauling device adapted to run on a single rail including a roller rolling along the top of the rail with its axis parallel to the top surface of the rail, means for pre-

- venting the device from lifting from the rail, and an upwardly extending, automatically operating car engaging dog. 65
2. A car hauling device adapted to run on a single rail including a plurality of longitudinally spaced apart rollers engaging with the rail at different places along the rail, means for preventing the device lifting from the rail, and an upwardly extending, automatically operating car engaging dog. 70
3. A car hauling device adapted to run on a single rail including a plurality of longitudinally spaced apart rollers engaging with the top surface of the rail at different places along the rail, means for preventing the device lifting from the rail, and an upwardly extending, automatically operating car engaging dog. 75
4. A car hauling device adapted to run on a single rail including a plurality of longitudinally spaced apart rollers engaging with the rail at different places along the rail, means for preventing the device lifting from the rail, and an upwardly extending, automatically operating car engaging dog located between said rollers. 80
5. A car hauling device adapted to run on a single rail including a plurality of longitudinally spaced apart rollers engaging with the top surface of the rail at different places along the rail, means for preventing the device lifting from the rail, and an upwardly extending, automatically operating car engaging dog located between said rollers. 85
6. A car hauling device adapted to run on a single rail including a plurality of longitudinally spaced apart rollers engaging with the rail at different points along the rail and an upwardly extending, automatically operating car engaging dog mounted on the device intermediately said rollers. 90
7. A car hauling device adapted to run on a single rail including a plurality of rollers, one roller with its cylindrical periphery bearing on top of the rail head and another of the rollers bearing underneath the rail head. 95
8. A car hauling device adapted to run on a single rail including a plurality of rollers, one roller with its cylindrical periphery bearing on top of the rail head and another of the rollers with its cylindrical periphery bearing underneath the rail head. 100
9. A car hauling device adapted to run on a single rail including a plurality of rollers, one roller with its cylindrical periphery bearing on top of the rail head and another of the rollers bearing underneath the rail head approximately directly beneath said first-mentioned roller. 105
10. A car hauling device adapted to run on a single rail including a plurality of rollers, one roller with its cylindrical periphery bearing on top of the rail head and another of the rollers with its cylindrical periphery bearing underneath the rail head approximately directly beneath said first-mentioned roller. 110
11. A car hauling device adapted to run on a single rail including a body structure extending along the rail, a roller near one end of the body rolling upon the top surface of the rail head, a cooperating roller rolling on the under surface of the rail head, a car engaging dog mounted centrally on said body, a roller near the other end of said body rolling along the top surface of the rail head and a cooperating roller rolling on the under surface of the rail head. 115
12. A car hauling device adapted to run on a single rail including two plates, extending along the rail at either side thereof, and spaced away from the rail to permit travel of the device around curves in the rail, and rollers located near the ends of said plates and rolling on the top and bottom surfaces of the rail head. 120
13. A car hauling device adapted to run on a single rail including two plates, extending along the rail at either side thereof, and spaced away from the rail to permit travel of the device around curves in the rail, and rollers located near the ends of said plates and rolling on the top and bottom surfaces of the rail head. 125
14. A car hauling device adapted to run on a single rail and including vertical plates extending along each side of the rail, rollers between the plates above the rail, and a car engaging dog pivotally supported between the plates. 130
15. A car hauling device adapted to run on a single rail and including vertical plates extending along the rail, rollers between the plates above the rail, and rollers carried by the plates and engaging beneath a portion of the rail, and a car engaging dog pivotally supported between the plates. 135
16. A car hauling device adapted to run on a single rail and including vertical plates extending along the rail, rollers between the plates above the rail, a car engaging dog pivotally supported between the plates, and cable attaching means at each end of the plates. 140
17. A car hauling device adapted to run on a single rail and including vertical plates extending along the rail, rollers between the plates above the rail, and rollers carried by the plates and engaging beneath a portion of the rail, a car engaging dog pivotally supported between the plates, and cable attaching means at each end of the plate. 145

In testimony whereof, I have signed my name to this specification.

MERITT HUTTON.
